(57) **CLAIM**

We claim the ornamental design for an electronic access device, as shown and described.

DESCRIPTION

FIG. 1 is a top perspective view of an electronic access device in accordance with the present design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

Any broken lines shown in the drawings are for illustrative purposes only and do not form a part of the claimed design.
